UNITED STATES PATENT OFFICE.

CHRISTIAN NESSEN BRUHN, OF CEDAR FALLS, IOWA.

EGG CRATE.

Application filed September 25, 1922. Serial No. 590,442.

To all whom it may concern:

Be it known that I, CHRISTIAN NESSEN BRUHN, a citizen of the United States of America, and a resident of Cedar Falls, 5 Black Hawk County, Iowa, have invented certain new and useful Improvements in Egg Crates, of which the following is a specification.

My invention relates to improvements in 10 egg crates and the like, and the object of my improvement is to furnish a box-like crate having an open side, adapted to receive and hold tiers of card-board cellular sections for holding eggs, permitting the removal of the 15 sections sidewise instead of at the top, and having a closure for said open side, with easily separable fastening devices to secure said closure in place removably.

This object has been attained by the means 20 which are hereinafter described and claimed, and which are illustrated in the accompanying drawings, in which Figs. 1 and 2 are respectively perspective views of my improved egg crate, with the closure shown removed 25 in Fig. 1 and as fastened in place by my improved fastening devices, in said Fig. 2.

The box-like egg crate shown is of the usual type and construction, having an elongated form, with ends 1, top 2, bottom 30 3 and rear side 4, all rigidly secured together, and having a vertical medial partition 8. The forward side or closure 5 for the open side is a flat board having a vertical row of horizontally elongated slots 9, and having each end notched to provide vertically spaced horizontally elongated recesses 10 which are similar in size to said slots 9.

The partition 8 divides the interspace of the crate into two equal spaces, and in each 40 compartment thus provided is placed a vertical tier of cellular card-board egg-holding sections 6, which may be removed singly sidewise through the open side of the crate, by means of an improved scoop and clamp- 45 ing holder shown in a co-pending application.

The means for removably fastening the closure 5 in place are thus described. The

numeral 7 denotes screw-eyes fixed in vertical alinement in the partition 8 and also in 50 the side edges of the ends 1.

These screw-eyes pass through the oppositely positioned notches 10 and slots 9, the eyes projecting a little outwardly of the closure. Bendable metal rods 11 have their 55 upper ends headed or bent into rings 12 and are passed downwardly through the eyes of said screw-eyes 7 outside of the closure 5 but in contact therewith, and the lower extremities of the rods below the lowermost 60 screw-eyes may be bent at 13 to prevent the escape or detachment of the rods, but when these bends 13 are bent back to restore the rods to their straightness, they may be readily withdrawn to permit removal of the closure by a sidewise movement over the screw- 65 eyes.

This method of construction of an egg crate not only conduces to convenient removal of the cellular egg-holders, but the 70 fastening rods are accessible for removal, yet do not project enough to catch in surrounding objects, and are inexpensive in construction and in assemblage.

Having described my invention, what I 75 claim as new, and desire to secure by Letters Patent, is:

A crate having one longitudinal side open and having a partition leading to the open side, a closure plate for said open side having 80 over said partition edge a row of openings and having over each abutting end edge of the crate a row of longitudinal end recesses, screw-eyes inserted in said partition and in 85 said crate edges traversing said openings and said recesses respectively with their eyes extending beyond the outer face of the closure plate, and rods passed through the rows of 90 said eyes, each rod having a head wider than the opening in the abutting eye, and the other end of each rod being bendable about the abutting eye to removably secure it in place.

Signed at Waterloo, Iowa, this 23d day of August, 1922.

CHRISTIAN NESSEN BRUHN.
